UNITED STATES PATENT OFFICE.

JOHN PARKINSON, OF LOS ANGELES, CALIFORNIA.

ILLUMINATING SPEEDOMETER-INDICATOR.

1,116,619.

Specification of Letters Patent. Patented Nov. 10, 1914.

Application filed March 20, 1913. Serial No. 755,782.

To all whom it may concern:

Be it known that I, JOHN PARKINSON, a citizen of the United States, residing at Los Angeles, in the county of Los Angeles and State of California, have invented certain new and useful Improvements in Illuminating Speedometer-Indicators, of which the following is a specification.

My invention relates to an improvement in illuminating speedometer indicators, and the object is to provide a device of this character which may be attached to an automobile or other vehicle at a point to be visible to a person in the vehicle and also to persons on the outside, and connected operatively therewith so that as the speed varies a light of a different color will be displayed.

A further object is in the construction of the device in such a manner that when a light of one color is displayed to a person outside the vehicle, a light of a similar color will be displayed to the occupant, from which he can determine the speed at which the vehicle is moving.

A still further object is to construct the indicator so that during the day the speed will be indicated in numbers and at night the same numbers will be illuminated so that the operator may determine speed in this manner. Also the mileage will be indicated at speeds between those at which the various colored lights are shown.

This invention consists of certain other novel features of construction and combinations of parts which will be hereinafter fully described and pointed out in the claims.

In the accompanying drawings—Figure 1 is a longitudinal vertical sectional view; Fig. 2 is a horizontal sectional view on the line 2—2 of Fig. 1; Fig. 3 is a horizontal sectional view on the line 3—3 of Fig. 1; Fig. 4 is a sectional view on the line 4—4 of Fig. 1, and Fig. 5 is a view in perspective of the rotatable color-screen.

The casing A is provided with a bracket 1 by which it may be attached to the dash of the vehicle or at some other convenient point. The casing A has an opening 3 in its upper end, and a cover 4 is constructed to be received over and screwed down upon the rim 5 for closing this opening. An electric bulb or other suitable lighting means is held suspended in the upper portion of the casing A. An opening 6 is formed in the front of the casing preferably in line with

the point at which the strongest light rays are cast from the lighting means B. A suitable lens 7 is supported in the opening and a reflecting sleeve 8 extends for a short distance into the casing. A similar opening 9 is formed in the rear of the casing A, preferably at a point below the light center. This opening has a transparent covering 10 and a sleeve 11 similar to those in the opening 6.

A color screen C is rotatably mounted on a partition 12 secured about half-way up in the casing, and a speedometer or other operating means connected to be actuated by the movement of the vehicle is located beneath the partition and connected with the spindle 13 of the color screen in such a manner that it will be oscillated as the operative means is actuated due to changes in speed in the motion of the vehicle.

Suitable thrust-bearings 14 may be provided between the base 15 of the color screen and the partition 12 for reducing friction to a minimum.

As shown in the present instance, the color screen C has virtually two sets of screens, an upper ring *a* and a lower ring *b*. Each of these rings has six screens and at the line of division between the screens ray partitions 16, 16 are connected which extend from the base 15 to the full height of the color screen and project inwardly with just sufficient clearance from the light bulb B to permit of the rotation of the color screen. A greater or less number of colors may be used as desired for more closely showing the speed. In the present arrangement, it is assumed that a scale of light colors and the number of miles at which each color should be shown has been arranged as follows:—a white light up to twelve miles per hour; a yellow light up to fifteen; orange from fifteen to twenty; blue, twenty to twenty-two; green from twenty-two to twenty-five; and red to indicate any speed above twenty-five miles an hour which is the maximum speed permitted in most localities. The light screens of the upper ring *a* would then be arranged as better shown in Fig. 3, in the following manner:—screen *c* would be of white light; screen *d* of yellow; *e*, orange; *f*, blue; *g*, green; and *h*, red. In the lower ring, as shown in Fig. 4, the white glass *c'* would be arranged diametrically opposite to the white glass *c* of the ring above, and the yellow, orange, blue, green and red

glasses *d'*, *e'*, *f'*, *g'*, and *h'* respectively will be arranged in a corresponding manner diametrically opposite to a similar screen of the ring above. With this arrangement of the screens, the speedometer will be so connected to the spindle 13 that the rotation of the color screen will be in the direction of the arrow in Fig. 2, and will be so gaged that when the speed is above twelve miles an hour the screen *c* of the upper ring will move from before the opening 6, and *d* will replace it, thus causing the rays from the lamp B passing through the lens 7 to be changed from white to yellow. As the speed increases, the other light-screens will be brought before the opening 6 in the ascending scale, and, if the speed be decreased, in the descending scale.

As the upper and lower rings *a* and *b* are connected together, it will be understood the several color screens will be correspondingly changed, and that as the color of the light is changed through the opening 6 a like light will be displayed to the occupant of the vehicle through the opening 9.

As a means of indicating the speed during the day, a frame work 18 carried on the upper end of the cylinder C has a transparent screen 19 mounted therein and on this transparent screen numbers are placed to indicate the mileage as the cylinder is oscillated. An opening 20 is formed through the upper portion of the casing on the same side as the opening 9 or toward the operator and a pointer 21 is secured in this opening to point out the number indicating the speed of the vehicle.

As convenient means of causing the cylinder C to be oscillated by the movement of the vehicle, I have provided in the casing A below the partition 12 a gear 22 connected to the spindle 13 by which the cylinder is moved. A compound gear wheel has the gears 23 and 24 formed thereon and is mounted on a spindle 25 in position to have the gear 24 in mesh with the gear 22 connected on the spindle 13. A rack bar 26 is mounted in guides 27 and 28 so that the teeth thereof are engaged with the gear 23 and as the rack bar is moved through the guides, the compound gear 23-24 will cause the gear 22 and spindle 13 to be moved and thus the cylinder will be oscillated. A link 29 is pivotally connected at its one end to the partition and a pin 30 carried by the end of the rack bar 26 works in a slot 31 near the center of this link.

A flexible shaft 32 is connected in any convenient manner, not shown, to be operated by the movement of the vehicle. This shaft extends up and is connected to rotate a governor shaft 33 journaled in a bearing 34 in the bottom of the casing A. A governor 35 is connected to the shaft 33 within the casing and is of standard form having

the grooved collar 36 which is moved by the centrifugal force exerted upon the governor to actuate the mechanism control.

A bell crank lever 37 is pivoted at 38 at its bend to the casing and one end of the bell crank lever has pins 39 received in the slot of the collar 36. A pin 40 is carried by the free end of the bell crank lever and works in a slot 41 in the lower end of the link 29; thus as the speed of the flexible shaft 32 varies the bell crank lever is moved, actuating the rack bar 26 and oscillating the cylinder, C.

It will thus be seen that I have provided a luminous indicator which will display a light to both the occupant of the vehicle and a person outside the vehicle to indicate the speed at which the vehicle is moving, which will give to the operator readings in figures of the speed either in the day or at night and will give the mileage between the speeds indicated by the changes of the color of the light rays, and one which, if required by the laws of the State or locality in which the vehicle is operated, would tend to discourage persons who might otherwise be tempted to exceed the speed limits. Also, that when installed the device cannot readily be tampered with to inaccurately calibrate the speedometer to display the low-speed indicating lights at high speed.

It is evident that more or less slight changes might be resorted to in the form and arrangement of the several parts described without departure from the spirit and scope of my invention, and hence I do not wish to be limited to the exact construction herein set forth, but—

Having fully described my invention, what I claim as new and desire to secure by Letters Patent is—

1. A luminous indicator constructed to be used in connection with a mechanism for transmitting motion from the moving parts of a vehicle, comprising a casing rigidly connected at any suitable point, a light in the casing, said casing provided with a plurality of openings therethrough so the light will be visible from several sides, a tubular frame located in the casing around the light, a set of screens of several colors mounted in the frame between one of said openings and the light, a similar set of screens mounted in the frame for each of the remaining openings, and placed so that as the frame is turned the rays cast through each opening will be of the same color, and means connecting said frame with the motion-transmitting mechanism to cause the frame to be turned to a greater or less degree as the speed of travel of the vehicle is varied and thus indicate the rate of speed.

2. A luminous indicator constructed to be attached to a vehicle and operated by the movement thereof comprising a casing rig-

- idly connected to the vehicle, a light in the casing, said casing provided with front and rear openings so that the light will be visible to the occupant of the vehicle and to a person without the vehicle, a tubular frame within the casing around the light, a series of color screens mounted in the frame around the circumference thereof in line with the forward opening, a similar series of color screens mounted in reverse order in the frame in line with the rear opening, and means connecting said tubular frame with the moving part of the vehicle for causing it to be turned as the vehicle is propelled to indicate the speed at which the vehicle is traveling.
3. A luminous indicator for vehicles constructed to be used in connection with a mechanism for transmitting motion from a moving part, comprising a casing, a light supported within the casing, said casing provided with a plurality of openings spaced around the circumference thereof through which the rays of light are visible, a tubular frame received within the casing around the light and a plurality of the sets of screens of different colors arranged around the circumference of the frame in such a manner that as the frame is turned the color of the rays cast through said openings is changed simultaneously, and means connecting the frame with said motion-transmitting mechanism to cause the frame to be turned to indicate the rate of travel of the vehicle.
4. A luminous indicator constructed to be used in connection with means for transmitting motion from the moving parts of a vehicle, comprising a casing, a light supported within the casing, a tubular frame received around the light and connected to be oscillated by the motion-transmitting means, upper and lower color rings carried by said frame, a plurality of divisions of various colors composing the circumference of each ring, the divisions of the upper and lower rings being of the same color values, and similarly consecutively arranged with the exception that like colors are diametrically opposite, a transparent screen mounted on the tubular frame and having a plurality of numbers thereon to indicate the distance, said casing having openings diametrically opposite, and one in line with each of said color rings so that as the frame is oscillated the color of the rays as cast through the openings is changed simultaneously, the casing provided with an opening in line with the transparent screen and a pointer located in said opening to indicate one of said numbers and designate the speed at which the vehicle is traveling.
5. A luminous indicator constructed to be used in connection with a means for transmitting motion from a moving part of a vehicle comprising a casing, a light supported within the casing, a tubular frame received around the light and connected to be oscillated by the motion transmitting means, upper and lower color rings carried by said frame, a plurality of divisions of varying colors composing the circumference of each ring, the divisions of the upper and lower rings being of the same color values, and similarly consecutively arranged with the exception that like colors are diametrically opposite on the two rings, said casing having an opening adjacent the upper ring through which the rays from the lamp will be visible to a person outside the vehicle, and as the color of the rays is changed the speed will be indicated, and provided with an opening diametrically opposite said first opening and in line with the lower ring of the color screen through which the rays of the light are visible to the occupant of the vehicle, and by the corresponding changes in the color of the rays the speed is indicated.
6. A luminous indicator constructed to be used in connection with a means for transmitting motion from a moving part comprising a casing, a light supported within the casing, said casing having an opening through which the rays of light are cast to be visible to a person outside the vehicle, a frame carrying a plurality of screens of different colors mounted between said light and opening to be actuated by the motion transmitting mechanism for changing the color of the rays cast through the opening to indicate the speed, a screen carried by the frame to be moved with it, said casing being provided with an opening through which the screen is visible, said screen being provided with a plurality of numbers spaced at predetermined intervals throughout the length of the visible portion of the screen, and a pointer located in the opening to indicate one of said numbers, which number will designate the speed at which the moving part is traveling.

In testimony whereof I affix my signature, in the presence of two witnesses.

JOHN PARKINSON.
